INVENTOR.
FRANK F. HOSMER.

BY *Martin C. Smith, Atty.*

UNITED STATES PATENT OFFICE

2,034,814

TRUSS

Frank F. Hosmer, Glendale, Calif.

Application April 14, 1933, Serial No. 666,142

1 Claim. (Cl. 128—99)

My invention relates to a truss for the treatment and correction of either single or double abdominal hernia and the principal object of my invention is, to generally improve upon and simplify the construction of the existing forms of trusses and to provide a truss that is relatively simple of construction, inexpensive of manufacture and which may be worn without undue discomfort and inconvenience to the wearer.

10 Further objects of my invention are, to provide a truss having a wide range of adjustability in order that it may be conveniently worn by persons of different sizes and fitted so that the spring pressed pad will yieldingly engage directly upon the hernia and further, to construct the truss so that the resilient metal straps or bands that carry the spring pressed pad will not make direct contact with the body of the wearer while the truss is in proper position for use.

20 With the foregoing and other objects in view, my invention consists in certain novel features of construction and arrangements of parts that will be hereinafter more fully described and claimed and illustrated in the accompanying drawing in which:

Fig. 1 is a top plan view of a truss constructed in accordance with my invention.

Fig. 2 is a vertical section taken on the line 2—2 of Fig. 1.

30 Fig. 3 is a vertical section taken on the line 3—3 of Fig. 2.

Fig. 4 is a vertical section taken on the line 4—4 of Fig. 2.

Fig. 5 is a vertical section taken on the line 5—5 of Fig. 2.

Fig. 6 is a vertical section taken on the line 6—6 of Fig. 5.

Fig. 7 is a horizontal section taken on the line 7—7 of Fig. 2.

40 Fig. 8 is an elevational view looking against the inner face of the resilient arm that carries the hernia engaging pad.

Fig. 9 is an elevational view similar to Fig. 2, with parts broken away and showing the form of truss constructed for double hernia.

Referring by numerals to the accompanying drawing which illustrates a preferred embodiment of my invention, 10 and 11 designate the flat straps or bands of resilient metal, preferably steel, the inner portions of which bands overlap each other, as illustrated in Fig. 1, and suitably secured to the outer ends of these bands are straps 12 of leather or fabric.

55 The ends of the straps that are connected to

the metal bands are suitably padded to afford comfort to the wearer of the truss.

Carried by the free ends of the straps 12, are disc-shaped pads 13 of suitable material that are adapted to bear on the back of the wearer's body and projecting outwardly from the ends of the straps that carry said pads 13, are headed studs 14.

A strap 15 has one end detachably mounted on one of the head studs and the other end of this strap is provided with apertures 16, whereby the strap may be adjustably connected to the other one of the studs 14 and thereby hold the truss in proper position upon the wearer's body.

The metal bands or straps 10 and 11 are provided with longitudinally disposed slots 17 and passing through these slots adjacent to the inner end of band 10, is a clamping screw 18 that receives a nut 19, thereby adjustably securing the inner ends of the resilient metal bands to each other.

The lower end of a vertically disposed resilient metal arm 20 that curves inwardly from the front faces of the bands 10 and 11, is secured by means of a clamping screw 21 and nut 22 to the overlapping portions of the bands 10 and 11 at a point between the clamping screw 18 and the inner end of band 10.

25 Inasmuch as the bands 10 and 11 are longitudinally slotted, this upstanding arm 20 may be adjusted lengthwise upon the overlapping portions of said bands.

30 The upper end of the inwardly projecting arm 20 carries a pad 23 that is adapted to yieldingly engage the body at a point above the horizontal plane occupied by the truss and thereby tending to hold said truss in proper position with the bands 10 and 11 spaced apart from the adjacent surface of the body.

35 One end of a resilient metal strap or band 24 carries a relatively thick hernia engaging pad 25 and the opposite end of this resilient arm is provided with an aperture 26 that is surrounded by a series of radially disposed ribs 27 and which latter are formed on the face of the band that is positioned adjacent to band or strap 10.

40 Interposed between this perforated end of the resilient arm 24 and the band 10, is a washer 28 having a ribbed face that is adapted to engage the ribs 27 on arm 24 and projecting from the 45 edge of this washer into the slot in band 10, is a lug 29. This lug holds the washer against rotary movement relative to the band 10 and arm 24.

50 55 Passing through the perforation 26 in arm 24,

through the washer 28 and through the slot in resilient band 10, is a clamping screw 30 that receives a nut 31 and the latter bearing on the outer face of band 10. This clamping screw 30 5 enables the resilient pad carrying arm 24 to be secured to the resilient band 10 in differently adjusted position lengthwise of said resilient band and when the clamping screw is loosened to permit disengagement of the ribs 27 with the ribbed face of washer 28, the pad carrying arm 24 may be swung upwardly or downwardly so as to bring the pad 25 into position to exert pressure on the abdominal wall directly over the hernia.

15 By tightening screw 30, the pad carrying arm 24 is securely fastened in its adjusted position to the resilient band 10.

The clamping screw 18 and nut 19 provide simple and efficient means for securing the resilient bands 10 and 11 to each other in different- 20 ly adjusted positions and likewise the clamping screw 21 and nut 22 provide means for securing the lower end of the pad carrying arm 20 to the overlapping portions of the bands 10 and 11 in 25 differently adjusted positions.

When the truss is properly applied to the body and strap 15 is secured to the studs 24, the padded ends of the straps 12 and the body engaging pad 23 maintain the metal bands 10 and 11 in position spaced apart from the body of the wearer and the flexing of the resilient arm 24 outwardly 30 away from the body of the wearer imparts tension to said arm so that the pad 25 engages with yielding pressure directly upon the abdominal 35 wall over the hernia.

The hernia engaging pad 25, together with the body engaging pads 13 and 23 provide four points of contact between the truss and the wearer's body and these contacts, together with the engagement of the straps 12 with the body, effect- 40 ually retains the truss in proper position upon the body and permits ordinary body movements without disturbing the position of the hernia engaging pad 25.

45 In Figs. 1 and 2, the pad carrying arm 24 is shown in position for applying pressure to a hernia on the righthand side of the body and to apply pressure to a hernia on the lefthand side of the body, the position of the resilient arm 24 50 is reversed and its outer end is connected to the slotted portion of arm 11.

In Fig. 9 I have illustrated a modified form of the truss wherein two resilient pad carrying

arms 24 are provided for the treatment and cor- 5 rection of double abdominal hernia and in this construction the resilient arms are bent vertically intermittent their ends so that the hernia eng- 10 aging pads carried by the inner ends of said arms may occupy substantially the same horizontal plane.

Thus it will be seen that I have provided a truss that is relatively simple in construction, in- 15 inexpensive of manufacture and very effective in performing the functions for which it is intended.

It will be understood that minor changes in the size, form and construction of the various parts of my improved truss may be made and substi- 15 tuted for those herein shown and described with- 20 out departing from the spirit of the invention, the scope of which is set forth in the appended claim.

I claim as my invention:

In a truss, the combination with a pair of 20 bands of resilient metal arranged in overlapping relation, said bands being provided with coinciding longitudinally disposed slots, of straps of 25 flexible material having their ends permanently secured to the outer ends of said bands, body en- 30 gaging pads secured to the free ends of said flexible straps and arranged on the inner faces thereof, a stud carried by the free end of one of the straps on the outer face thereof, a short 35 strap secured to the free end of the other strap, said short strap being provided with apertures 40 for the reception of said stud, releasable means passing through the slots in said resilient metal bands for adjustably clamping the end of one of 45 said bands to the intermediate portion of the other band, a short vertically disposed resilient 50 arm adjustably and detachably connected to the overlapping slotted portions of said bands, a pad carried by the upper portion of said resilient arm, an elongated resilient arm, means for de- 55 tachably and adjustably connecting one end of 40 said elongated resilient arm to one of the slotted bands between the point where said slotted band is connected to the other slotted band and the 45 end of said band to which the flexible strap is 50 connected, said elongated resilient band being 55 curved inwardly away from the overlapping slotted portions of said first mentioned bands so that its end terminates adjacent and in front of the 60 short vertically disposed pad carrying arm and a 65 body engaging pad carried by the free end of 70 said elongated resilient band.

FRANK F. HOSMER.
